UNITED STATES PATENT OFFICE

118,169

DESIGN FOR AN INFLATABLE WATER SWING

Betty Ella Prince, Loris, S. C.

Application July 25, 1939, Serial No. 86,237

Term of patent 14 years

To all whom it may concern:

Be it known that I, Betty Ella Prince, a citizen of the United States, residing at Loris, in the county of Horry and State of South Carolina, have invented a new, original, and ornamental Design for an Inflatable Water Swing, of which the following is a specification, reference being had to the accompanying drawing, forming part thereof.

I claim:

The ornamental design for an inflatable water swing, as shown.

BETTY ELLA PRINCE.
